UNITED STATES PATENT OFFICE.

VALENTINE MLETSCHNIG, OF NORWICH, CONNECTICUT.

BOTTLE CLOSURE.

Application filed June 24, 1924. Serial No. 722,104.

This invention relates to an improved closure for bottles of the type having shouldered or beaded necks.

What I aim to do is to provide a novel bottle closure which can be used in lieu of the common crown cap now universally used, the present closure being such in construction that it obviates the necessity of requiring special machines for capping bottles and 10 subjecting them to breakage. Not only will the new cap be found advantageous at the time of application, but it will be found equally as advantageous when removing the cap for it can be readily taken off without the use of a special bottle opener and without causing breakage of the glass such as 15 happens when crown caps are used.

It is also a feature of the present invention to provide a structure which will form 20 an effective fluid seal, yet will permit the escape of destructive gases upon loosening the cap slightly.

As a result of the foregoing, the closure will be found comparatively simple in construction and inexpensive to use despite the 25 fact that it may cost a fraction more in money to manufacture, this being true in view of the fact that the construction provided assures the liquid tight seal and safety 30 means for gradually removing explosive gases.

Other features and advantages of the invention will become apparent from the following description and drawings.

35 In the accompanying drawing forming a part of this specification, and in which like numerals are employed to designate like parts throughout the same:

Figure 1 discloses a side elevation of a 40 bottle closure constructed in accordance with this invention, showing the same applied to the neck of a bottle.

Figure 2 shows a central vertical section through Figure 1.

45 Figure 3 is a cross section taken on line 3-3 of Figure 2.

In carrying out the invention, I employ a substantially cylindrical split sleeve 1 which is adapted to surround the neck of the bottle in slightly spaced relation, and which is provided at its top with an inturned flange 2 forming a shoulder for engagement with one of the beads B on the bottle neck N. The sleeve is indented with annular grooves 50 4 providing screw threads.

Cooperative with the sleeve is a closing

cap 5 which is adapted to telescopically receive the upper portion of the sleeve and which has its skirt portion provided with screw threads 6 for engaging the threads of 60 the sleeve. A packing disk 7 is adapted to be interposed between the bottle neck and the cap as shown more clearly in Figure 2. The skirt of the cap is provided with an opening 8 through which a locking pin 9 is 65 adapted to project, this locking pin being carried by the free end of a spring 10 fastened to the cap. The head on the inner end of the locking pin is adapted to be positioned in the slot formed by the spaced split ends 70 of the sleeve. This arrangement prevents relative rotation of the cap with respect to the sleeve. I might state here that the opening 8 is of a size to permit the pin to be entirely withdrawn therethrough to facilitate screwing on of the cap. Furthermore, I might state that while I have shown the slot in the sleeve as being disposed substantially vertical, I wish it to be understood 75 that it may, if desired, be disposed diagonally.

In practice, the sleeve is slipped over the neck of bottle prior to the attachment of the cap. The split in the sleeve permits it to expand to accommodate the diameter of the 80 bottle and since the sleeve will preferably be of resilient material, its flange forming shoulder will snap beneath the bead on the bottle to hold the sleeve in place. With the sleeve in place, the cap is simply threaded 85 onto the sleeve by rotation of one with respect to the other. At this time, the spring 10 is held outwardly with the finger to prevent interference of the locking pin with the relative rotation of the parts. As soon 90 as the cap has been screwed on sufficiently air tight, and assuming that the locking pin is then opposite the slot, the spring is released and the pin is projected into the slot 95 to serve as a lock to then prevent further rotation of the cap with respect to the sleeve. Where the closures are used simply for domestic purposes, I have found that the locking pin and spring may be eliminated, if 100 desired. Where, however, the bottle is to be shipped, it is much safer to use the supplemental locking device.

Although I have shown and described the specific embodiment of the invention, it is to be understood that minor changes coming 110 within the scope of the appended claims, may be resorted to, if desired.

I claim:

1. In combination, a bottle having a neck and exterior bead thereon, a sleeve about the neck and having an inturned flange at its upper end opposed to said bead and also having intermediate portions bearing against the outer side of the neck, and a screw-threaded cap detachably connected with said sleeve.
- 10 2. A bottle closure comprising a resilient split sleeve adapted to surround a beaded bottle neck, said sleeve having its upper end inturned to provide a stop flange for engagement with the bead and being further provided with an exterior indenture and an interior projection forming a screw thread, a screw threaded cap adapted to threadedly engage said sleeve, and a locking device carried by said cap and adapted
- 15 3. A bottle closure comprising a resilient split sleeve having one end directly laterally
- 20 to cooperate with the slot provided between the spaced ends of the sleeve for preventing relative rotation of the cap to the sleeve.
- 25 4. A bottle closure comprising a resilient split sleeve having one end directly laterally

inward to provide a stop flange, said sleeve being provided with an annular indentation forming a screw thread, a closing cap having its skirt provided with a screw thread for co-operation with the aforesaid screw thread, said skirt being also formed with an opening, a spring carried by said cap, and a laterally extending pin carried by the free end of the spring and adapted to project through the opening in said skirt into the slot formed between the spaced ends of said split sleeve.

4. A bottle closure comprising a sheet metal sleeve split throughout its height and adapted to surround a bottle neck provided with a bead, the said sleeve having at its upper end an inturned flange abutting against the bead and bearing against the side of a bottle neck, and also having an exterior indenture and an interior projection forming a screw thread, and a screw threaded cap adapted to threadedly engage said sleeve.

In testimony whereof I affix my signature.
VALENTINE MLETSCHNIG.
